UNITED STATES PATENT OFFICE.

JOSEPH E. BAINES, OF PITTSBURGH, AND JACOB P. BOSLE, OF MOUNT OLIVER, PENNSYLVANIA, ASSIGNEES TO NATIONAL TUBE COMPANY, OF PITTSBURGH, PENNSYLVANIA, A CORPORATION OF NEW JERSEY.

ROLLER CHUCK.

Application filed April 6, 1922. Serial No. 550,210.

To all whom it may concern:

Be it known that we, JOSEPH E. BAINES and JACOB P. BOSLE, citizens of the United States, and residents of Pittsburgh and Mount Oliver, respectively, both in the county of Allegheny and State of Pennsylvania, have invented certain new and useful Improvements in Roller Chucks, of which the following is a specification.

This invention relates to work holding devices and more particularly to roller chucks having a plurality of roller jaws for gripping the work, and has for one of its objects the provision of a chuck primarily adapted for holding pipe couplings in a coupling screwing machine.

Another object is to provide a chuck of this class having removable cam plates which may readily be replaced when worn.

A further object is to provide a chuck that may readily be adapted to hold couplings of various sizes by substituting smaller cam rings and roller retaining rings.

A still further object is to provide a chuck having the novel design, constructions, and combination of parts described in the following specification and illustrated in the accompanying drawings.

In the drawings, Figure 1 is a side elevation partly in section of our improved chuck attached to the positively driven hollow spindle or barrel of a coupling screwing machine.

Figure 2 is a front end elevation thereof.

Figure 3 is a sectional elevation on the line III—III of Figure 1.

Figure 4 is a fragmentary detail plan of the roller retaining ring showing the means for holding the rollers in place.

Referring more particularly to the drawings, the numeral 2 designates the main body portion or rim of the chuck, which is adapted to be rigidly secured to the positively driven barrel 3 of a coupling threading machine or like part of a similar machine. In the drawings the rim or body portion 2 of the chuck is shown secured to the barrel 3 of a coupling threading machine by bolts 4.

A cam ring 5 is mounted within the body portion 2 and is held against rotation relative to the portion 2 by keys 6 and 7 se-

cured in key-ways 8 and 9, respectively, formed by registering slots in the cam plate and the portion 2.

The cam ring 5 is provided with a plurality of transversely extending recesses or slots 10 on its inner peripheral surface which have their end walls 11 inclined or beveled inwardly and upwardly, and one end of the slots is formed deeper than the other. Cam plates 12, which have their end walls 13 correspondingly beveled, are removably mounted in said slots 10, the beveled end walls 13 of the plates cooperating with the end walls 11 of the slots 10 to form a dovetailed connection, and one end of said plates will project downwardly from the cam ring a greater distance than the other, due to one end of the slots being deeper than the other. The cam ring is also cut away on each side of the slots 10 to form a roller path or travelway 14.

A roller retaining ring 15, mounted for rotary movement within the cam ring 5, is provided with an outer flange portion 15^a adapted to abut the outer edges of the cam ring 5. The roller retaining ring 15 is provided with a plurality of transverse outwardly diverging slots 16. That is, slots having a substantially V-shaped cross section. A roller jaw member 17, mounted within each of the slots 16 is adapted to project therethrough and engage the work which is shown in the drawing as a pipe coupling A. The diameter of the roller jaws is greater than the narrowest or bottom portion of the slots 16 so that they will be retained therein, and these rollers have their forward ends beveled as at 17^a in order to facilitate entering the work in the chuck.

The cam plates 12, due to their angular position with relation to the inner periphery of the cam ring and the outer periphery of the roller retaining ring, will engage the rollers or jaws 17 when the roller retaining ring 15 is rotated clockwise and force the roller jaws downwardly through the slots 16 into engagement with the work A, and when the roller retaining ring 15 is rotated in the reverse direction, or counter-clockwise, the roller jaws will be disengaged from the cam plates. That is, the roller jaws will be moved to a position opposite

the highest portion of the cam plates and consequently will be loosened from engagement with the work member A.

Handles 18, secured to the flange 15^a of 5 the roller retaining ring 15, are adapted to be gripped by the operator to turn the ring to engage or disengage the jaws 17 with the work.

In order to prevent the jaws 17 from becoming displaced when inserting or removing the roller retaining ring 15 from within the cam ring 5, a locking clip 17^b may be provided, as shown in Figure 4. The clip 17^b fits within a groove 17^c in the face of the 15 roller jaw and has its ends engaged in suitable apertures in the ring 15.

If it is desired to use the chuck for smaller work than it will engage, as originally assembled, the cam ring and roller retaining ring may be removed and a cam ring having the same outside diameter as the one removed, but a smaller inside diameter is substituted, together with a smaller roller retaining ring, thus providing a chuck assembly suitable for smaller work without removing the main chuck body from the barrel 3.

It will be understood that while this invention is described and illustrated as a 30 chuck for use on power driven machines it may be used to grip work in various operations. For instance a handle may be formed integral with or secured to the body portion 2 and the device used as a hand wrench if

desired, and it is to be particularly understood that the word chuck as used in this specification and claim is to be construed broadly enough to include any such gripping devices.

While we have only shown one preferred embodiment of our invention we do not wish to be limited thereto since various modifications may be made without departing from the spirit and scope of our invention as defined in the appended claim.

We claim—

A chuck comprising a main body portion, a cam ring removably secured to said body portion, a plurality of cam plates having beveled end walls and removably fitted into 50 slots having beveled end walls in the inner face of said cam ring, a roller retaining ring mounted within said cam ring and adapted to move relative thereto, said roller retaining ring being provided with a plurality of 55 transverse slots having a substantially V-shaped cross section, and a plurality of roller jaws mounted in said slots in said roller retaining ring and adapted to be engaged by said cam plates when said roller ring is rotated relative to said cam ring, said cam plates being adapted to force said roller jaws into engagement with the work.

In witness whereof, we have hereunto signed our names.

JOSEPH E. BAINES.
JACOB P. BOSLE.
